DESIGN FOR A GAME APPARATUS FOR PIN BALL GAMES

Herbert G. Breitenstein, Chicago, Ill.

Application August 31, 1935, Serial No. 58,384

Term of patent 3½ years

To all whom it may concern:

Be it known that I, Herbert G. Breitenstein, a citizen of the United States, residing at Chicago, in the county of Cook and State of Illinois, have invented a new, original, and ornamental Design for a Game Apparatus for Pin Ball Games, of which the following is a specification, reference being had to the accompanying drawing, forming a part thereof.

The figure is a perspective view of the game apparatus for pin ball games, showing my new design.

I claim:

The ornamental design for a game apparatus for pin ball games, as shown.

HERBERT G. BREITENSTEIN.
